UNITED STATES PATENT OFFICE.

HENRY L. DOHERTY, OF NEW YORK, N. Y.

VENTILATION.

1,382,961.

Specification of Letters Patent. Patented June 28, 1921.

Continuation of applications Serial Nos. 633,367, 633,368, and 633,369, filed June 15, 1911; also Serial No. 701,873, filed June 5, 1912, and Serial Nos. 855,235 and 855,236, filed August 7, 1914. This application filed December 15, 1916. Serial No. 137,107.

To all whom it may concern:

Be it known that I, HENRY L. DOHERTY, a citizen of the United States, residing at New York, in the county of New York and State of New York, have invented certain new and useful Improvements in Ventilation, of which the following is a specification.

This invention relates to ventilation; and it comprises a method of and apparatus for producing a constant flow of air to and from a building while maintaining a constant temperature in said building irrespective of whether said temperature be higher or lower than that prevailing outside said building, wherein the incoming air is caused to undergo temperature interchange with the outgoing air, and is also cleaned and scrubbed, by means of circulating currents of water or other liquid, any deficit of heat or cold (as the case may be) remaining after such interchange being made up in other ways but advantageously by the use of power; all as more fully hereinafter set forth and as claimed.

Heating of buildings is of course a well developed art while positive cooling is seldom attempted save in the case of refrigerating establishments. Positive cooling is not used to any extent for office buildings and the like. Ventilation is usually effected in a more or less haphazard manner, the general rule being that air is supplied to a room and allowed to escape as it will through the porosity of bricks and structural material, leakages at windows and the like. Where heating is by hot air, this air is heated in a furnace or the like and supplied to the rooms, the air already present being allowed to escape in any manner it may. Where heating is by radiators and the like, as a rule exchange of air in a room is allowed to take care of itself. In all these methods, the heat carried by the escaping air is of course lost; there is no provision for recovering it.

In the present invention I have substituted for these more or less haphazard ways of heating and ventilating a positive method of ventilation wherein the temperature of the building or room is maintained at a fixed point by interchange of heat between flowing incoming air and outgoing air. The temperature plane so fixed and main-

tained may be higher than that of the outside air, in which case the method may be considered a heating method, or it may be lower than that of the outside air in which case the method is one of cooling. In so doing, where the building is to be maintained warmer than the outside air, the heat units which are ordinarily wasted in the usual methods of heating and ventilation are picked up by the incoming air and restored to the room or building. I find that by the use of a simple heat interchanging system it is as practicable to keep a building cool as it is to keep it warm; and with the type of apparatus hereinafter described this change from heating to cooling may be done by simply adjusting a valve or two; the process and apparatus operating in the same manner whether heat is transferred from the outgoing air to the incoming air (in warming) or from the incoming air to the outgoing air (in cooling).

My invention is particularly useful in connection with cold storage plants, drying kilns and houses, assembly halls, theaters and office buildings and the like.

In heating or cooling a building with theoretical heat interchange, the temperature of the building would of course remain fixed, whatever the rapidity of current of incoming and outgoing air. But theoretical efficiency in heat interchange is not to be secured and there are, further, radiation losses. Heat is radiated from the windows and walls of very warm buildings in cold weather, while in hot weather heat is radiated inwardly in the same manner. This unavoidable deficit in heat or in cold I make up in a suitable manner. As will be seen, in the case of heating a building in the present manner, however, I merely require to make up this deficit; not to supply an indefinite amount of heat units to be lost by being radiated and carried away from the building. The amount of heat therefore to be supplied is much less than in the ordinary methods of operation.

In producing the heat interchange between incoming and outgoing air currents I find it best to use circulating bodies of liquid which is advantageously water, since heat interchange can be carried farther between a gas and a liquid than between two

gases separated by a metal wall; this being particularly the case where the differences in temperature between the air currents undergoing interchange are small; as is necessarily the case in ventilating buildings.

In the present invention therefore, in its most advantageous embodiment, I produce circulating currents of liquid which pass between the two air currents. The same liquid circulating in a closed circuit, may first be brought into contact with one current and then with the other current; but I find it better to operate in a more special manner, using a plurality of flows of liquid and interchanging between pairs of such flows. In making up the deficit of heat or cold remaining after the interchange I find it best to use pumping means located in the circuit and operating on vapors of the liquids used for heat interchange. With any pump operating on vapors, heat is of course developed on the compression side and absorbed on the suction side. Use of power for imparting or withdrawing heat is practicable in this relation since after all it is merely a deficit which is to be made up; the main heating or cooling being done by heat interchange.

Advantageously I divide the operation of treating the incoming and the outgoing air into a plurality of successive stages. In this treatment, which for the sake of brevity I may call "conditioning" hereinafter, by the use of currents of water in direct contact with the air I am enabled to accomplish several other results than that of the heat interchange hereinbefore discussed. The incoming air is always more or less dusty and it is desirable that it be cleaned and scrubbed. It is also desirable that the air supplied to the rooms have an adjusted moisture content; being neither too moist nor too dry. This adjustment and scrubbing to free the air of dust may both be effected by the liquid currents used for heat adjustment in the present method.

I shall now describe an advantageous embodiment of my invention as applied where the temperature to be maintained in the room or building is above that of the outer air. The outer air is drawn or forced in by a suitable pump or fan through a chamber where it is cooled and scrubbed by a body of water circulating in a closed path. This path may include a filter for catching the accumulated dust and dirt. This body of water I cause to circulate through a metal heat interchanger of any suitable type; and on the other side of the metal walls in the heat interchanger I cause to circulate in a closed path a similar body of liquid, which is brought into intimate contact with the air current removed from the room. The second stated current of liquid abstracts heat from the outgoing air and transfers it

through the heat interchanger to the first stated circulating body which then gives it up to the air which it is scrubbing. Passing this scrubbing device the air next enters another chamber where it is brought into similar contact with another body of liquid traveling in a closed circuit. In this closed circuit is interposed a vapor chamber with which communicates a pump. Suitable connections enable this vapor chamber to be placed under either pressure or suction from said pump. In the present instance, it will be on the compression side of the pump. This body of liquid completes the warming up of the air and any deficit of heat which the air may have after undergoing the stated heat interchange will be here made up; being made up by the power of the pump. After contact with the two bodies of water in the manner stated, the air will of course be saturated with the moisture at the temperature prevailing in the heating chambers. So much moisture is not desirable in air to be delivered to a room. I therefore run the apparatus in such a manner that the temperature at which the air leaves contact with the bodies of liquid is somewhat below that at which it is desired to enter the room and then filter out the mist of water which is usually present and reheat a little further. This reheating is best done by heat taken from the outflowing air from the room but may also be accomplished by the use of a small heater, such as a steam heater. In a similar manner outgoing air from the building in the instance just discussed is first used to raise the temperature of the conditioned air to get rid of the saturation mentioned, is then caused to flow through a spray chamber or the like where it gives up its heat to a circulating body of liquid which is the same as the first one hereinbefore mentioned; that which travels through the heat interchanger and gives up heat to the body of liquid scrubbing the incoming air. After passing this chamber, the air next goes through another chamber wherein it is contacted with another current of liquid; this latter current of liquid traveling in a closed path including a vapor chamber which is on the suction side of the stated pump. The air gives up its heat to this body of liquid and the pump removes vapors from the body of liquid and transfers them to the compression in the manner before stated. The outgoing air may now be allowed to escape. In cooling the building the working of the apparatus is simply reversed so that the air now travels in the reverse direction. As just described, the heat of the outgoing air was transferred to the incoming air. In this cooling operation the heat of the incoming air is transferred in exactly the same manner to the outgoing air. The operation is exactly the same.

In the accompanying illustrations, I have shown, more or less diagrammatically, organizations of apparatus elements adapted for use in the described process. In this 5 showing:

Figure 1 is a diagrammatic plan of one assemblage of apparatus elements for carrying out my process;

Fig. 2 is a diagrammatic illustration of 10 a somewhat different form of apparatus;

Fig. 3 is a vertical diagrammatical section through a building showing the arrangement of the air conduits and a portion of the operating plant;

Fig. 4 is a more or less diagrammatic plan 15 of an actual working construction and arrangement of the apparatus shown diagrammatically in Fig. 2;

Fig. 6 is a similar longitudinal section through the apparatus from the discharge side on line 6-6 of Fig. 4;

Fig. 7 is a vertical section through the 25 heat transferring apparatus J;

Fig. 8 is a similar view of a slightly modified form of heat transferring apparatus J;

Fig. 9 is a partial section in partial elevation 30 of the washer;

Fig. 10 is a vertical section through the spray chamber;

Fig. 11 is a section through the manometer;

Fig. 12 is a longitudinal section of the 35 water eliminator;

Fig. 13 is a perspective view of the ventilating system illustrated in Fig. 2, showing its relation to the rooms of the building to 40 be heated and ventilated.

Referring to the drawings (Figs. 3 and 45 13), 1, 2, 3, 4, 5, 6, 7, 8 and 9 indicate several rooms of a building. A¹, A², A³, A⁴, A⁵, A⁶, A⁷, A⁸ and A⁹ indicate one set of air flues leading to registers D¹, D², D³, D⁴, D⁵, D⁶, D⁷, D⁸ and D⁹, set in the base boards of the rooms. B¹, B², B³, B⁴, B⁵, B⁶, B⁷, B⁸ and B⁹, indicate another set of air flues leading to registers C¹, C², C³, C⁴, C⁵, C⁶, C⁷, C⁸ and C⁹ set near the ceiling of the corresponding rooms, the registers of both these sets of air flues advantageously being set in the walls of the rooms so that the air will always be discharged into the rooms in 55 a horizontal direction. 10 indicates a trunk main to which the flues A are connected, while 11 indicates the trunk main to which the flues B are connected. The trunk mains 10 and 11 are connected with the heating chamber 37 by the conduit 70. Valves 71 and 72 permit establishing or shutting off the communication between 70 and 10 and 11 respectively. A similar connection 73 having branches 74 and 75 provided with 60 valves 76 and 77 and connected to conduits

10 and 11 respectively, permits establishing or shutting off communication between 10 and 11 and the washer 31 as shown in Figs. 2, 6 and 13 or spray chamber 60 in the modification shown in Fig. 1. When the apparatus is working as a heater, the valves 72 and 76 are open, and 71 and 77 are closed. When operating as a refrigerator, the position of the valves is reversed, 71 and 77 being open, while 72 and 76 are shut. It is obvious that if desired, this apparatus may be so arranged and the operating means so connected that the shifting may be performed from a single control.

E¹, E², E³, E⁴, E⁵, E⁶, E⁷, E⁸ and E⁹ are 80 dampers on the flues B, while F¹, F², F³, F⁴, F⁵, F⁶, F⁷, F⁸ and F⁹ are dampers on the flues A. G¹, G², G³, G⁴, G⁵, G⁶, G⁷, G⁸ and G⁹ are tubes running from the tube 13 of the pressure indicator to the respective 85 rooms 1, 2, 3, etc. and are each provided with valves respectively designated by adding the letter "a" to the numeral designating the respective tubes.

14, 15 and 16 are tubes running from the 90 tube 17 to points on the side wall of the building. These tubes terminate at a middle point of the side wall of the first, second and third stories respectively and are in free communication with the outside air. Corresponding pressure tubes 18, 19 and 20 and 95 21, 22 and 23 run to the middle portion of the end wall of the respective stories. Another set (not shown) runs to the other side wall of the building. Each of these pressure tubes is provided with a cock, 14^a, 15^a, etc. The trunk tubes 13 and 17 are connected respectively to the pressure chambers 24 and 25 on the magnifying manometer. As shown in Fig. 11, one of the two sides of the 100 manometer is filled with oil and the other with water. The line of division between the two when 24 and 25 are under equal pressure should be at the middle of the oil leg which is numbered 0 on the scale. The 105 two pressure chambers 24 and 25 have areas which are large relative to the cross section of the U-tube. As will be readily perceived, the relative level of the liquids in the respective chambers 24 and 25 will depend 110 upon the pressure difference between them. For instance, if the pressure in 24 is the highest, the level in 24 will fall, while the level in 25 will rise. The line of division between the oil and water will therefore fall 115 through a length of the oil leg of the U-tube which will have a volume equal to that of the displaced oil. The amount of movement of the line of demarcation relative to the difference in pressure will manifestly depend 120 upon the ratio of the cross section of the other chamber 25 (if the difference is measured in terms of the water column) to the cross section of the U-tube. I am thus able to open the cock on the pressure tube con-

necting the oil chamber of the manometer (in the arrangement shown) with any room and the other chamber of the manometer with the corresponding pressure tube to the atmosphere, to detect very small differences in pressure between any room and the atmosphere. Since it is necessary for the successful operation of my invention that there shall be no short circuiting of air from the atmosphere to the room or vice versa, it is very important to keep the pressures in the rooms as nearly equal to that exerted by the atmosphere on the exposed wall as possible. Noting pressure conditions from the manipulations of the manometer, the operator can easily bring the pressure to the requisite balance by operating dampers E and F, or if necessary, regulating the speed of the fans.

27 is the downcast air conduit conducting the fresh intake air, while 28 is the upcast conduit for the impure air discharged from the building.

The fan 29, Figs. 1, 2, 4 and 5, draws the fresh outside air through the conduit 27 and forces it into the washer 30. Here it is contacted with water which usually has substantially the temperature of the air discharged from the building. The water for scrubbing in 30 may be directly contacted with the discharged air in washer 31, or the scrubbing water for circulation through the respective chambers may be kept separate and the heat transferred from one body of water to the other in a heat interchanger 32. Interchanger 32 may be simply of the tubular heater type or of any other type of apparatus preferred in which two bodies of water are caused to flow along opposite sides of metallic surfaces. I have found it advantageous to use an apparatus in which it is possible to permit the hotter current to enter at the top and the cooler current at the bottom. In this way I avoid convection currents and so maintain a maximum temperature difference between the two currents during their flow through the apparatus.

In 30 the fresh air is either heated or cooled according to whether the outside air is hotter or cooler than the inside air, and 50 thoroughly scrubbed for the elimination of dust. 30 may be of any construction which will insure thorough contact of air and water or saline solution. It may be of such design that the air is forced to pass through a number of water curtains 30' (Figs. 4 and 5).

In the form of construction shown in Fig. 9, the chamber 30 contains a number of tiers of horizontal transverse troughs 62, the troughs 10 of the adjacent tiers being set staggered, and the intervals between the troughs being such that each in a tier (except the outside ones of the tiers having the largest number of troughs) receives one-half of the discharge 65 of the troughs of the tier above which it is placed. The upper edges of the troughs 62 are notched. The feeder trough 63 runs transversely to the troughs and narrow vertical slots located just above the troughs of the first tier so that water discharges into 70 the upper troughs from each side of the feeder trough. The water overflows from the troughs of the upper tier and in each case cascades or rains down to the two troughs of the next tier placed to right and 75 left of the particular trough considered. The air enters at the bottom and passes up to the top of the chamber and is thus forced to pass through a large number of water currents formed by the water overflowing 80 from the troughs. Circulating pumps 64 and 65 supply the scrubbing solution to the washers 30 and 31.

From 30 the air passes through conduit 100 to the spray chamber 33. Here it is subjected to contact with a jet of steam or warm or cold water as described below according to the temperature of the atmosphere. The spray chambers 33 and 60 are designed to bring the air into intimate contact with the steam or liquid supply—the cold liquid being used when the apparatus is being used as a cooler. Any apparatus which is capable of reducing the liquid to a very fine spray may be used.

If the system is acting as a heater, live steam may be blown into the air from steam pipe 34 which is provided with a regulating valve 35. This steam serves both to heat the air and at the same time to humidify it. 100 The quantity of steam used should be that which will raise the air from the temperature at which it leaves the washer 30 through conduit 100 to about 60° F., more or less. The air discharging from 33 usually carries 105 a heavy fog of condensed steam or of fine particles of water spray, according to whether the apparatus is being used as a heater or cooler.

This spray is eliminated in the water 110 eliminator or separator 36. 36 may be of any approved construction. Any good type of tar separator used in purifying illuminating gas may be made to answer the requirements. The one shown is made up of a 115 large number of corrugated plates 36' (see Figs. 12 and 13) set up so that their surfaces are parallel with each other and leave an interval of about one-half inch between them. In operation, the air passing between 120 the curved surfaces of the plates at a rapid rate develops considerable centrifugal effect upon suspended water particles (the corrugations are made about 6 to 8 inches deep) which are thrown against the walls of the 125 passage. These are in operation covered with a thin film of the liquid which serves to separate and retain any dust particles which may have escaped precipitation in the washer.

The steam from the pipe 34 serves to supplement the action of the washer. If, as with some temperature conditions may be the case, the washer 30 is able to raise the air to about 60° the steam injection may be omitted. It is used when the washer or other means for taking heat from the outgoing air current (as is generally the case) is not able to properly condition the air. To do this it is necessary to communicate to the air per unit weight an amount of moisture which, when the air is at the temperature at which it is supplied to the rooms, will give it the relative humidity desired. This is usually from 65 to 80 per cent. according to the preference of the individual. In cold weather a rather high humidity is preferable since it supplements the warming effect of the hot air by reducing the amount of heat from the bodies of the occupants through the excessive evaporation of moisture. In warm weather, on the other hand, a low humidity is desirable since it promotes the direct cooling of the bodies of the occupants by increasing the evaporation of the perspiration. By using a proper quantity of steam in 33 it is always possible to properly condition the air no matter how cold the external atmosphere.

When steam is not easily available the conditioning of the air may be effected by loading the air with a heavy mist or fog in the spraying chamber 33 and, by-passing the water eliminator, passing the air current to the heating coils 37. Here the water will be evaporated by the heat from the coils as the air rises in temperature and consequently increases in vapor-carrying capacity. It is, of course, necessary in this method of operating to see that only the proper weight of water per pound of air is loaded on the latter in the spray chamber.

After passing through or around the water eliminator, as the case may be, the air passes to the coils 37. Here it is heated to a temperature of about 65° to 75° according to the temperature desired in the rooms. If the air be saturated with vapor at 60° and then raised to 72° it will have just about the humidity desirable.

From 37 the air passes through pipe 70 to the air trunk conduit 11 and from 11 it is distributed to the various flues B¹, B², B³, B⁴, B⁵, B⁶, B⁷, B⁸ and B⁹, leading to the upper registers C of the several rooms, the heated air spreads across the room in contact with the ceiling and gradually descends as the lowest stratum of air is removed and fresh air flows in above, without mixing to any great extent with the partially contaminated air occupying the lower part of the room. By thus preventing convection currents and positively renewing the air of the rooms instead of constantly diluting a partially contaminated atmosphere, as is

done in the ordinary method of building ventilation, I am able to secure a given standard of purity in the room atmosphere with a rate of circulation much less than is required to obtain the same standard of purity by ordinary methods of ventilation.

In order to give greater flexibility to the heating and to enable the occupants of each room (within certain limits) to adjust the temperature to their individual liking, I provide an ordinary hot water or steam system. In the arrangement shown, water is heated in the heater 65' by steam from the pipe 66. The steam discharges through the nozzle 61 in the return main, thus aiding the circulation of the water as well as heating it. The hot water then flows through the pipes 68 to the radiators 69 in the rooms. As shown, these are located in an enlargement of the air flue and heat the air just as the latter discharges into the rooms. By this arrangement I avoid the establishment of local convections which would interfere with the movement of the air through the rooms according to my plan. It is true that by thus locating the radiators, I prevent the direct heat radiation to the bodies of the occupants which takes place when the radiators are located in the rooms. But as the heating by the radiators is purely auxiliary and they are of small surface, this drawback is practically negligible.

The air finally reaches the lowest level of the rooms and discharges from the same through the registers D into the flues A of the respective rooms, thence through the trunk main 10 to the spray chamber 60 or the washer 31 according to the form of apparatus. When using the apparatus of Fig. 1 as a heater and ventilator the spray chamber 60 fulfills no function other than that of providing passage of the outgoing air to the washer 31, which is of the same construction as washer 30. Still considering the apparatus as a heater the outgoing air in washer 31 is subjected to scrubbing by water which has been cooled in 32 by the cold water flowing from the washer 30. The cooling of the air causes condensation of more or less of the water vapor which the air carries out of the rooms—the amount condensed depending upon the degree of cooling to which the air is subjected in 31.

By proper designing and operation the heat given up to the incoming air in 30 is thus in great part withdrawn again in 31 from the outgoing air. The evaporation in 30 and condensation in 31 requires that at intervals a proper proportion of the water from the washer 31 circuit shall be transferred to the washer 30 circuit. With theoretically perfect working of the heat interchanging apparatus I the total expenditure of heat would be represented by the heat supplied by the coils 37 and the greater or less amount of

heat required to discharge the air in the saturated condition instead of in the partially saturated condition in which it is received into the system. The latter heat quantity includes the latent heat of the vapor carried by the effluent air over that carried by the air at the intake and any excess of sensible heat due to the fact that, owing to imperfect working of the apparatus, the temperature of the effluent air is seldom or never as low as that of the air at the intake. This ideal can, of course, never be completely realized in practice. With even an 80 per cent. efficiency of heat transfer from 31 to 30, however, the B. T. U. required to heat a given building, even under severe winter conditions, will be less than 40 per cent. of the B. T. U. that would be required with the usual methods of heating.

20 The air discharging from 31 passes to the exhaust fan 40. From 40 the air passes through the up-cast conduit 28 to some level above the roof of the building where it is discharged into the atmosphere.

25 When working as a refrigerating and ventilating process in the summer time, the action of the apparatus is as follows:

The warm atmospheric air, as before, is drawn into the system through conduit 27 by 30 the fan 29 and forced through the washer 30. Here, as before, it is scrubbed by water, only in this case the water is initially cooler than the air by a range of temperature depending upon the excess of atmospheric temperature over the room temperature. The water is cooled in the interchanger 32 by the counter circulation of the water from the washer 31 through which the relatively cold air discharging from the rooms passes. Be-

40 sides abstracting sensible heat from the air, in this case the washer 30 must absorb the latent heat of the considerable quantity of water vapor condensed from the fresh air. Owing to inefficiency in heat transfer and to

45 the heat increments which the air receives in the building and conduits, it is never possible to maintain a given temperature (say 72°) in the building, even though once established, by the unaided action of the washers 30 and

50 31. In order to maintain the rooms at the desired temperature it is therefore necessary to exert on the fresh air an additional refrigerating effect. This end I accomplish by

55 coming to the outgoing air current through the medium of the heat transferring apparatus J.

I have lettered as J a particular heat transferring mechanism wherein a vapor pump is 60 located between two chambers one of which on the suction side the pump, temporarily at least, serves as an evaporator, while the other which is temporarily at least on the pressure side of the pump, serves as a condensing chamber. By reversing the connections the

evaporator becomes a condenser and the condenser an evaporator. In the chamber on the suction side of the pump, the pressure being lowered, there is evaporation and cooling while in the chamber on the pressure side 70 there is condensation of the liquid and development of heat. In both the evaporator and the condenser it is desirable to have a large surface of liquid exposed to the atmosphere of the chamber under pressure or suc- 75 tion.

The heat transerrer J of Fig. 7 comprises an evaporator, 41, a condenser, 42, and a vapor pump, 43. The evaporator 41 has a vaporizing chamber, 44, containing a 80 plurality of troughs, 45, a barometric leg, 46, and the reservoir and seal-tank 47. The spray chambers 33 and 60 are also a part of the refrigerating apparatus since it is in 85 33 that the air receives its final cooling by being contacted with the cold water produced in J and in 60 that the condenser water is cooled by the cool effluent air. The water warmed by contact with the air in 33 is drawn off from the bottom of the same 90 through pipe 44^a and lifted to the transverse trough 48 which feeds the upper tier of troughs 45. By means of the vapor pump 43 the pressure in 44 is maintained at about .254 pound which corresponds to the maximum tension of water vapor at 60° F. 95 Since the water leaves the spray chamber at a much higher temperature, depending upon the temperature at which the air discharges from 30 and the volume of water circulated, etc., on entering the chamber 44 it immediately boils at the expense of its own heat. As the water falls from trough to trough more and more of it is vaporized, the residuum approaching closer and closer to the 100 temperature corresponding to the vapor tension in the chamber (preferably .254 pound absolute) until it finally reaches the bottom of the chamber 44, under the assumed conditions, usually at a temperature of 60° F. 110 From the chamber 44 it gradually descends through the barometric tube 46 as the water is drawn from the tank 47, until it finally reaches the tank and is pumped thence again to the sprays of chamber 33 through pipe 115 47^a. The vapor formed in 44 is forced by the vapor pump 43 into the condenser chamber 49 of condenser 42. 49 contains a filling of troughs, 50, similar to the troughs 45, the upper tier of 50 being fed from the transverse trough 51. Water from the spray chamber 60 on the exhaust air circuit is drawn into the trough 51 and from thence passes to the upper tier of troughs 50. 120 From the troughs 50 of the upper tier the water overflows and cascades to the troughs of the tier below. These are placed halfway between the troughs of the upper tier so that each trough receives approximately one-half of the overflow from the troughs of the 125

first tier on each side of it. The water passes thus from tier to tier in intimate contact with the vapor filling the chamber 49, taking up heat from the vapor and condensing it. An air pump, 55, removes from the chamber 49 of 42 or from chamber 44 the air which is carried into the chamber by the two currents of circulating water. The circulation of water is maintained sufficiently rapid to keep the chamber at a temperature of about 80° (or slightly above if necessary). The condensed vapor mingles with the water circulating through 49 and 60, and the current descends through the barometric tube of 42 into the seal-tank 54 and is pumped thence back to the spray chamber 60. If the temperature at which the water leaves the condenser chamber 49 is maintained at about 80° F. the vapor pump is only working against a pressure difference of .248 pound per square inch and the amount of power required is not serious. An air pump, 55, removes from 49 such air as is carried thereinto by the two bodies of circulating water—the air being absorbed by the water in the two chambers 33 and 60.

In Fig. 8 I have shown an alternative form of the structure of Fig. 7, like elements having like reference numbers. The difference is mainly in the form of interior subdividing or distributing device for bringing into intimate contact the liquid and the atmosphere of the chamber. In this form the water instead of being delivered on the trough-like elements of Fig. 7 is delivered into a series of perforated troughs 45' of chamber 41' and perforated troughs 50' of chamber 42' over which it runs from top to bottom giving a film-like exposure of the liquid to the atmosphere in the chamber. The barometric legs 46' are shown as passing into wells 47' and 54' in lieu of the tanks 47 and 54 of Fig. 7. Otherwise the two structures are the same.

As stated before, the air in passing through 33 is subjected to a fine spray of cold water, the water being obtained as described above. The spraying device in the chamber 33 consists of banks of spray nozzles 56' which receive water under pressure and spray it into the air current passing through chamber 33. The contact of this spray with the air from the washer 30 thoroughly cools the same. Usually the air will leave the washer 30 saturated or nearly saturated after depositing a large part of its vapor contents and parts with still more water in 33. Arrangements must be made to have the air discharge from 33 at such a temperature that the vapor carried by the saturated air will correspond to the proportion of vapor desired in the rooms.

On leaving 33 the air will be heavily loaded with fog or spray. To remove this it is passed through the water eliminator

36, where the suspended water is removed from the air. It thence passes through the coil chamber 37 which has, of course, no function during the refrigerating operation and is simply left in the air circuit to avoid the labor of changing the arrangement of the apparatus when changing from a heating to a refrigerating operation. The air next passes to the trunk main 10 and from 10 through the flues A¹, A², etc., to the lower registers D of the rooms. Discharging from the registers D, the air spreads across the room as a fairly horizontal stratum which gradually rises as it is displaced by fresh air from D. The air discharges from the rooms through the upper registers C and flues B to the trunk main 11, which is, in this case, connected to the spray chamber 60 on the exhaust side of the circuit or to the washing chamber 31 in the apparatus of Fig. 2. It is to be noted that by introducing the cold air into the rooms at the bottom I avoid to a great extent the mixing of the fresh air with the partially vitiated air in the room, just as in the heating operation I avoid the same thing by introducing the hot air at the top of the rooms. While the air usually enters the flues A at approximately 60 to 65°, owing to the heat which it receives in passing through the flues from the relatively hot walls, it discharges into the rooms at about 70°. In passing through the rooms it is increased in temperature by heat conducted from the atmosphere and that generated by the individuals in the rooms, and at the same time picks up the moisture and contaminating matter exhaled by the occupants.

In the spray chamber 60 the air is subjected to scrubbing by the "atomized" water drawn off from the tank 54 of the condenser 42 of the heat transfferer J and pumped to the sprays of the chamber 60. Since the outgoing air usually has a humidity of only about 70 per cent. and is at a temperature of only about 75° while it leaves the spray chamber 60 at a higher temperature and saturated with water vapor the combined effects of the evaporation and transfer of sensible heat to the air from the water spray chamber 60 is to impart an amount of heat equivalent to the heat liberated in the condensation of the water vapor pumped from the evaporator 41 to 42 by the vapor pump 43. The unevaporated water is drawn from the bottom of the spray chamber and drawn back through the pipe 49^a to the top of the condenser chamber 49, where it condenses the vapor pumped into 49 from 41.

Under extremely high atmospheric temperatures the air in 60 may experience a rise of temperature of from 2 to 5°. It is seldom, however, that it is necessary to raise the temperature more than a couple of degrees and, as a rule, the saturation of the

air with moisture will furnish ample cooling effect to cool the condenser water. It is desirable that in 60 the air to be saturated to the maximum extent so that the maximum possible proportion of the cooling may be performed by evaporation, thus permitting the air to enter the washer 31 at the lowest possible temperature.

From 60 in the apparatus of Fig. 1 the air passes through a spray separator similar to that used in chamber 36 and enters the washer 31. This is similar in construction to 30 and requires no further description. Water which has been heated in the heat interchanger 32 by the water warmed by the incoming air in washer 30 is pumped into the feed trough 63 of washer 31, passes to the upper tier of troughs 62 and cascades from trough to trough forming water curtains through which the air must pass. The intimate contact between air and water causes a portion of the sensible heat of the water (which should be within two or three degrees of the temperature of the outside air) to be transferred to the air. Since the increase of the vapor carrying capacity of air increases very rapidly with the temperature above 70°—an increase in temperature from 70° to 80° causing an increase in vapor carrying capacity of 40 per cent. of its capacity at 70°, while a temperature rise of from 80° to 85° causes an increase in carrying capacity for vapor of over 34 per cent. of the capacity at 70°—the fact that the air usually enters the washer practically saturated does not interfere with the evaporation of more water in 31. The conditions of operation both in the spray chamber and in the washers depend upon the temperature difference between the building and the external air as well as upon the actual temperatures; but as a rule the cooling effect in 31 through evaporation much exceeds the cooling effect by conduction. As a consequence, the rise in temperature of the air in passing through 31 is usually not as great as the fall in temperature of the oppositely flowing water current.

From 31 the air passes to the exhausting fan 40 and from there to the up-cast conduit or stack 28 and discharges into the atmosphere.

The structure of Fig. 1 and Fig. 2 represent methods of transferring heat differing somewhat in detail. Supposing the apparatus to be warming incoming air, in the structure of Fig. 1 the warmest outgoing air, that passed through 60, gives up its heat to the warmer incoming air, that coming through 33 by means of the compression suction system J already described, while the less warm outgoing air, that in 31, exchanges heat with the cold incoming air, that in 30, by means of the flowing water system I. In Fig. 2 this arrangement is, so to speak, re-

versed since in the structure of Fig. 2 the cold incoming air, that in 30, exchanges heat with the warmest outgoing air, that in 31, by means of the flowing water circulation I, while the somewhat cooled outgoing air, that in 60, transfers heat to the somewhat warmed air, that in 33, through the compression suction system J. More specifically, as the apparatus is shown in Fig. 1 the air in 30 is exchanging heat with the air in 31 by means of the water circulation. The same body of water may go from 30, by propelling or drawing, by pump 64 through by-pass 200 and 202 to 31 and thence back to 205 and by-pass 201 to 30 the valves 82 and 83 in the heat interchanger 32 being closed; or if different bodies of water are used the water passes through 64 to the heat interchanger 32, the valves in 200 and 201 being closed and the valves 82 and 83 being open. Here it exchanges heat with water flowing on the other side of the heat interchanger by means of pipes 202 and 205. The exchange of heat between 33 and 60 is effected, the apparatus being in the act of warming up incoming air, by heating such air in 33 by somewhat warmed water from 47 passing to 33 through pipe 47^a and returning to 44 by means of pipe 44^a. Part of the warm water may be by-passed through a pipe 47^b to the coils 37 and returned to the pipe 47^a through a return pipe 47^c. Suitable valves 47^d, 47^e and 47^f are provided in the pipes 47^a, 47^b and 47^c for controlling the amount of water by-passed. While the operation pump 43 is extracting vapors under suction and delivering into 44 it would be also delivering heat to 44. Similarly, water from 60, which has been warmed by the outgoing air, passes through 49^a to suction chamber 49 where it yields vapor and heat and passes to 54 thence going to 54^a back to 60.

In Fig. 2, presuming as before that the apparatus is heating up incoming air, the air first passes into 30 where it is contacted with warmer water. This water, if a single body of water is used, comes from chamber 31 exposed to the warmest outgoing air and extracts heat therefrom. Between 31 and 30 it flows in continuous cycle by means of pipe 204, by-pass 201, by-pass 200 and pipes 202'. If different bodies of water are used for heat interchanging, then the water from 30 flows through pipes 84 and 84', the valves in 200 and 201 being closed, in continuous circuit through the heat interchanger where it exchanges heat with water similarly flowing in continuous circuit to and from 31 through conduits 202' and 204'. At the same time heat is being interchanged between 31 and 33 by the compression-suction system J. The apparatus being used to heat the incoming air, somewhat heated water passes into 33 from 130

hot well 47 by means of pipe 47^a, while water is returned to 44 through 44^a. Part of the warm water may be by-passed through a pipe 47^b to the coils 37 and returned to the pipe 47^a through a return pipe 47^c. Suitable valves 47^d, 47^e and 47^f are provided in the pipes 47^a, 47^b and 47^c for controlling the amount of water by-passed. In this operation pump 43 is delivering heat and compressed vapors into 44. Simultaneously, the air in 60 gives up some of its heat to flowing water which passes through 49^b into suction chamber 49 where it gives up heat and vapors where it passes to cold well 54, being delivered back to 60 from this cold well by 54^b.

It will be apparent that the fundamental idea underlying my process is the transfer from the outgoing to the incoming air, or vice versa, of the maximum possible quantity of heat, while at the same time providing for the establishment of the proper condition of humidity of the air. To aid this heat transfer when using the apparatus as a refrigerator the power of the air to carry latent heat through the medium of its water vapor is utilized to the greatest possible extent.

It is obvious that the temperature conditions in the different portions of my apparatus will vary with the variation of the temperature of the outside air, as well as with the difference between this and the temperature in the rooms. Therefore it is to be understood that the temperatures which I have given for the air in different portions of its circuit are simply given in the way of illustration and are not to be construed as limiting my invention to working within the exact temperature limits given.

What I claim is:—

1. The process of ventilating buildings which comprises passing air currents into and out of the building and transferring heat from the outgoing to the incoming current or vice versa through the medium of a liquid, while bringing the incoming current to a standard degree of absolute humidity.

2. The process of ventilating buildings which comprises passing air currents into and out of the building and transferring heat from the outgoing to the incoming current or vice versa by contacting first the warmer of the said currents and then the other of the said currents with water maintained in circulation between the two currents, while bringing the incoming air current to the desired degree of absolute humidity.

3. In a process of ventilating buildings the step of bringing the air for ventilation to the proper conditions of temperature and humidity which comprises transferring heat from the outgoing to the incoming air currents, saturating the incoming air with water

vapor and raising the temperature of the said incoming air current after it has been saturated with water vapor.

4. The process of ventilating buildings which comprises passing air currents into and out of the building, contacting the outgoing current of air with a body of water, contacting the incoming air current with a second body of water and transferring heat of the warmer body of water to the cooler body of water to condition the temperature and humidity of the air.

5. The process of ventilating and regulating the temperature of a building which comprises passing air currents into and out of the building, transferring heat from the outgoing air current to the incoming air current or vice versa by contacting both of said currents with separate bodies of water, establishing heat transferring relationship between the said two bodies of water, and continuing the circulation of the respective bodies of water in closed cycles to treat the respective air currents.

6. The process of ventilating and regulating the temperature of a building which comprises passing moist air currents into and out of the building, transferring from that one of incoming and outgoing air currents which has the higher temperature, to the other current, the major portion of the heat sensible and latent which it carries, condensing moisture from the initially warmer of the air currents and evaporating moisture into the initially cooler of the air currents.

7. In the ventilation of a building, the process which comprises drawing in an air current, subjecting the said air current to scrubbing by water, at such temperature as will transfer heat to said air, transferring to another body of water the temperature modification occasioned in the first body of water by the contact of the said incoming air therewith and subjecting an outgoing air current to scrubbing by the said second body of water.

8. In the ventilation of buildings, the process of bringing an incoming air current to the desired condition of temperature and humidity which comprises transferring from an outgoing air current to the incoming air current the maximum practicable quantity of the excess heat in the said outgoing air current over the said incoming air current, through the medium of a liquid, introducing a jet of steam into the said incoming air current, and subjecting the said air to a further heating by contact with heated surfaces.

9. In the ventilation of buildings, the process of bringing an incoming air current to the desired condition of temperature and humidity which comprises scrubbing the said incoming air current with a body of water

which has itself previously been heated by heat abstracted from an outgoing air current, injecting into the said incoming air current, after the same has been subjected to 5 the said scrubbing operation, sufficient steam to supersaturate the said air and raise the said air to a temperature corresponding to the dew point of the properly conditioned air, removing from the said supersaturated 10 air current substantially all suspended moisture, then passing the same in contact with heated surfaces to bring said air current up to the desired temperature and humidity.

10. In the ventilation of buildings, the 15 process of bringing an incoming air current to the desired condition in respect to temperature and humidity which comprises, scrubbing the incoming air current with water which has been heated by heat abstracted from an outgoing air current, introducing steam into the said incoming air until a temperature corresponding to the 20 dew point of the properly conditioned air is reached, separating from said air any 25 suspended water particles that may be left therein after treatment with said steam, subjecting the said air to a third heating to raise said air to a temperature suitable for heating the said building, scrubbing the outgoing air current with a second body of 30 water, said water being at a lower temperature than the initial temperature of the said outgoing air current, and transferring the heat absorbed by the said second body of 35 water to the said first body of water.

11. The process of conditioning air for ventilation which comprises heating the cooler one of intake and exhaust currents by heat transferred from the warmer current, and bringing the intake current to the desired temperature condition by evaporating water in heat-transferring relationship therewith or condensing water vapor in heat-transferring relationship therewith, according to whether the initial temperature 40 of the intake current is above or below the temperature of the conditioned air.

12. The process of conditioning air for ventilation which comprises heating the 50 cooler one of intake and exhaust air currents by transferring heat from the warmer to the cooler of said currents, and finally conditioning the said intake current by evaporating water in heat-transferring relationship therewith to cool said intake current and condense water vapor therefrom or by condensing water vapor in heat-transferring relationship with said intake current while contacting said intake current 55 with water to heat said current and to add water vapor thereto, according to whether the initial temperature of the said intake air is below or above the temperature of the conditioned air.

60 13. In the process of conditioning air for

ventilation, the step of transferring heat between intake and exhaust air currents in the direction of the current having the lower temperature which comprises transferring heat from the one of said currents 70 having the higher temperature to water by directly contacting said air with said water, and transferring heat from said water to the one of said currents having the lower temperature by directly contacting said 75 water with the said air current having the lower temperature.

14. In the process of conditioning air for ventilation the step of transferring heat from that one of intake and exhaust air 80 currents having the higher temperature to the other of said currents which comprises transferring heat from the said air current having the higher temperature to water and then transferring heat from said water to 85 the one of said air currents having the lower temperature.

15. The process of conditioning air for ventilation which comprises transferring heat from that one of intake and exhaust 90 air currents which has the higher temperature to a body of water, transferring heat from said body of water to a second body of water and transferring heat from said second body of water to that one of the said 95 intake and exhaust air currents which has the lower temperature.

16. The process of conditioning air for ventilation which comprises contacting that one of intake and exhaust air currents which 100 has the higher temperature with a body of liquid having a lower temperature than said higher temperature air current, transferring heat from said body of liquid to a second body of liquid, contacting said second body of liquid with said air current having the lower temperature to heat said air current, and spraying water into the 105 said air current having the lower temperature.

110 17. The process of conditioning air for ventilation which comprises contacting that one of intake and exhaust air currents which has the higher temperature with a liquid which is at a lower temperature to condense 115 a portion of the water vapor of said first mentioned air current to cool the same and to heat said liquid, contacting said heated liquid with the said air current having the lower temperature to heat said current, and spraying water into said incoming air current to add water vapor to said current.

18. The process of conditioning air for ventilation which comprises continuously passing a body of water into contact with 125 that one of intake and exhaust air currents which has the higher initial temperature, and removing the body of water from the air current, continuously evaporating part of the body of water removed from said air 130

- current, continuously condensing the vapor from said body of water to maintain rapid evaporation of said water, continuously circulating a second body of water into contact with said condensing vapor and into contact with that one of said currents which has the lower initial temperature, whereby heat is transferred from the first to the second of said air currents.
- 10 19. The process of conditioning air for ventilation which comprises continuously circulating a body of water into contact with that one of intake and exhaust air currents which has the higher initial temperature, continuously withdrawing vapor from part of said body of water while it is out of contact with said air current, continuously circulating a second body of water into contact with vapor from said first body of water, and then contacting said second body of water with the initially cooler of said air currents, to heat the same.
- 20 20. In a ventilating system having incoming and outgoing currents of air, the process of conditioning the incoming current of air which comprises maintaining a partial vacuum in a closed chamber containing water, maintaining a lower vacuum in another closed chamber also containing water, bringing water from the first of said closed chambers into intimate contact with one of said air currents, bringing water from the other of said closed chambers into intimate contact with the other of said air currents and transferring vapor from said lower vacuum chamber to said partial vacuum chamber.
- 30 21. The process of conditioning air for ventilation which comprises maintaining in a closed chamber a pressure such as will cause water to boil at a temperature below the desired temperature of the conditioned air, circulating water from said closed chamber into contact with that one of intake and exhaust air currents which has the higher initial temperature, transferring vapor from said chamber to a second chamber, maintaining in said second closed chamber a pressure such as will cause water to boil at a temperature above the desired temperature of the conditioned air, and circulating water from said second closed chamber into contact with that one of said air currents which has the lower initial temperature.
- 40 22. The process of conditioning air for ventilation which comprises maintaining in a closed chamber containing water a partial vacuum such as will cause water to boil at a temperature below the desired temperature of the conditioned air, continuously circulating water from said closed chamber in contact with that one of intake and exhaust air currents which had the higher initial temperature and then back to said closed chamber, maintaining in a second closed chamber containing water a pressure corre-
- sponding to the saturation pressure of water vapor at a temperature above the desired temperature of the conditioned air, transferring water vapor formed in said first chamber into said second chamber, continuously circulating water from said second closed chamber into contact with that one of said air currents which has the lower initial temperature, and returning said cooled water to said second closed chamber.
- 50 23. The process of conditioning air for ventilation which comprises continuously circulating water into contact with that one of intake and exhaust air currents which has the higher initial temperature, causing a portion of said water to evaporate under a pressure at which the water will boil at a temperature below the desired temperature of the conditioned air, continuously transferring water vapor formed by said evaporation into contact with a second body of water maintained at a pressure above the pressure prevailing in said first closed chamber, contacting said second body of water with that one of the said air currents which has the lower initial temperature, and maintaining a closed circulation of said water between said second body and said lower temperature air current.
- 60 24. The process of conditioning air for ventilation which comprises maintaining in a closed evaporating chamber an absolute pressure such as will cause water to boil at a temperature below the desired temperature of the conditioned air, continuously circulating water, first, into contact with that one of intake and exhaust air currents which has the higher initial temperature, the initial temperature of said water being below that of said air current, and, second, back to said evaporating chamber, continuously transferring vapor formed in said evaporating chamber to a condensing chamber which is maintained at a pressure above that of said evaporating chamber, circulating a second body of water through said condensing chamber, withdrawing water from said condensing chamber and contacting said water with that one of said air currents which has the lower initial temperature to heat said air and to cool said water, the rate of circulation of said water relative to the rate of flow of said air being regulated to that which will cause a heat transfer to said air from said water.
- 70 25. The process of conditioning air for ventilation which comprises maintaining a partial vacuum over a barometric column of water, continuously withdrawing water from the lower part of said barometric column and bringing said water into contact with one of intake or exhaust air currents, the temperature of said water being lower than the temperature of said air current, conducting the so-heated water back to the top of said barometric column to vaporize a part
- 75 80 85 90 95 100 105 110 115 120 125 130

of said water at the expense of its heat content, continuously transferring the so-formed water vapor into a barometric column condenser, passing water through said 5 condenser, continuously withdrawing water from the lower part of the barometric column of said condenser at substantially the same rate that water is added to said column at the top thereof, contacting the water being withdrawn with the other of said air currents to transfer heat to said latter air current.

26. The process of conditioning air for ventilation which comprises heating an intake air current in two steps, the first step 15 being carried out in contact with water heated by heat transferred from the outgoing air current, the heat and water vapor communicated to said air in said first step being regulated to that required to establish temperature and humidity conditions therein substantially corresponding to those which would be obtained in a properly conditioned air if reduced to its dew point, and 20 25 the second step being carried out by contacting the air with a heated surface to establish in said intake air the temperature and relative humidity desired.

27. The process of conditioning air for ventilation which comprises heating an intake air current by a portion of the heat of an exhaust air current, partly humidifying the partly heated air current with water vapor formed by heat abstracted from the 30 35 other of said air currents, subjecting the so-heated air current to further heating and humidifying by heat likewise withdrawn from the other of said currents and raised to a higher temperature potential.

40 28. The process of conditioning air for ventilation which comprises heating an intake air current by heat abstracted from an exhaust air current, humidifying the said air with vapor formed by heat abstracted 45 from the other of said air currents, subjecting the said air current to a second heating and humidifying step by contacting the said air with water heated by heat likewise abstracted from the other of said air currents 50 and raised in its temperature potential to a 55 temperature plane above that of the conditioned air.

29. The process of conditioning air for ventilation which comprises partly heating and humidifying an inlet air current by 55 60 contacting the same with water which has been heated by heat transferred from an outgoing air current, subjecting the inlet air current to a second heating and humidifying step by bringing the partially heated and humidified current into contact with water which has been heated by heat abstracted from the exhaust current and raised in its temperature potential, and subjecting the said inlet air 65 currents to a third heating step by passing

the same in contact with surfaces, the said surfaces being heated by water which has itself been heated by heat abstracted from the initially warmer of said air currents and raised in its temperature potential by mechanical means. 70

30. The process of conditioning air for ventilation which comprises partly heating and humidifying an intake air current by contacting the same with water which has been heated by heat transferred from an exhaust air current, contacting the partially heated and humidified current with water which has itself been heated by the condensation of vapor generated by heat abstracted from the initially warmer of said air currents, subjecting the intake air currents to a third heating step by passing the same in contact with a heated surface, the said surface being heated by water which has itself been heated by the condensation of water vapor generated by heat abstracted from the initially warmer of said air currents. 75 80 85

31. The process of conditioning air for ventilation which comprises contacting an exhaust air current with water to partially cool said air current, contacting the so-heated water with an intake air current to heat said air and to evaporate a portion of 90 95 said water into said air, contacting a second body of cold water with the partially cooled exhaust air current, continuously transferring the vapor formed from said second body of water into a condensing chamber 100 maintained at a pressure above the vapor tension of water at the temperature of the conditioned air, introducing a third body of water into said condensing chamber to condense said vapor, and subjecting the incoming air current to heating by the said third body of water in two steps, the first step comprising passing a portion of said third body of water in contact with surfaces in heat transferring relation with said intake air current and the second step comprising joining said portion of said third body of water with the remainder thereof and bringing the combined portions into contact with said intake air current. 105 110 115

32. The process of conditioning air for ventilation which comprises contacting an intake air current with water, contacting said water with an exhaust air current, subjecting a body of water to partial evaporation at the expense of its sensible heat, contacting the said cooled water after evaporation with one of said air currents after the latter has been contacted with said first mentioned water to further cool said air current and to heat said water, returning the so-heated water to said evaporating operation, continuously transferring water vapor from said water being evaporated to a condensing chamber, introducing water into 120 125 130

5 said condensing chamber to condense said vapor and to transfer the latent heat of said vapor to said water, contacting the so-heated water with the other of said air currents after the same has been contacted with said first mentioned water and returning said cooled water to said condensing chamber to condense a fresh portion of water vapor.

33. The process of conditioning air for ventilation which comprises withdrawing a portion of the heat of the warmer of intake and exhaust air currents and transferring the same to the cooler of said air currents through the medium of water with which it is brought in turn into contact in substantially counter-current relationship, further cooling said initially cooler current and reducing the absolute humidity thereof by bringing the same into intimate contact with 10 a second body of water of lower temperature, subjecting said second body of water to a partial vacuum sufficient to convert into vapor a portion of said second body of water, transferring the so-formed vapor into a condensing chamber which is maintained at a pressure higher than that at which said vapor was generated, contacting said vapor in said condensing chamber with a third body of water to condense said vapor and to 15 heat said water, and contacting the so-heated water with the initially cooler of said air currents after the same has been contacted with said first body of water to transfer to said initially cooler air current substantially the quantity of heat taken up by said body from said vapor.

34. The process of conditioning air for ventilation which comprises contacting the warmer of intake and exhaust air currents with a body of water to transfer a portion of its heat to said body of water, transferring said heat from said first body of water to a second body of water, and contacting said second body of water with the said cooler air current, contacting the warmer air current with a third body of water, contacting a fourth body of water with said cooler air current to further heat said air, subjecting said third body of water to a pressure corresponding to that of saturated steam at a temperature above the temperature of said fourth body of water to convert into vapor a portion of said third body of water, transferring the vapor so formed into a condensing chamber maintained at a pressure above the vapor tension of water at the temperature of the external air, and introducing said fourth body of water into said condensing chamber to condense said vapor.

35. The method of conditioning air for ventilation which comprises transferring from an exhaust air current to an intake air current the available portion of the heat carried by said exhaust air current above the initial temperature of the intake air, and

supplementing such heating of the intake air by evaporating a liquid in heat transferring relationship with the exhaust air, after the said heat has been abstracted therefrom, to withdraw a further quantity of 70 heat from said exhaust air below the temperature plane of the atmospheric air and condensing the vapor formed from said liquid in heat transferring relationship with said intake air.

36. The process of conditioning air for ventilation which comprises transferring from an exhaust air current to an intake air current a portion of the heat carried by said exhaust air current above the atmospheric 80 temperature, and further heating said intake air by abstracting a further quantity of heat from said exhaust air by evaporating water in heat-transferring relationship with said exhaust air and condensing said water vapor in heat-transferring relationship with said intake air to transfer said further quantity of heat to said intake air.

37. The process of conditioning air for ventilation which comprises transferring 90 heat from an exhaust air current to an intake air current, evaporating water in heat-transferring relationship with the cooled exhaust air to abstract a portion of its contained heat below atmospheric temperature 95 and compressing said vapor to a tension above the saturation pressure of water vapor at the desired temperature of the conditioned air, and passing said vapor in heat-transferring relationship with said intake 100 air.

38. The process of conditioning air for ventilation which comprises transferring from an exhaust air current to an intake air current, by circulating a liquid heat-carrying 105 medium in contact, in turn, with each of said air currents, evaporating water from a body of the same circulated in contact with said exhaust air to reduce the temperature of said water sufficiently below atmospheric 110 temperature to abstract the necessary heat from said exhaust air, compressing the water vapor formed to a pressure corresponding to the tension of water vapor at a temperature substantially above the desired temperature 115 of the conditioned air, and condensing said vapor by contact with a body of water maintained in circulation in contact with said intake air.

39. The step in a process of bringing air 120 to the proper condition of temperature and humidity for use in the ventilation of buildings, which comprises transferring from an outgoing air current to an incoming air current or vice versa according to which current 125 has the higher temperature, a portion of the excess heat carried by the one over that carried by the other, the said heat transfer being effected between the air of the incoming current during the first step in its treatment 130

and the air of the outgoing current as the last step in the treatment of said outgoing current prior to its being discharged into the atmosphere through the agency of a liquid heat-carrier.

40. The process of bringing air to the proper condition of temperature and humidity for use in the ventilation of buildings which comprises transferring from an outgoing air current to an incoming air current a portion of the heat carried by the outgoing air in excess of that carried by the incoming air, the said heat transfer being effected between the air of the incoming current as the first step in its treatment and the air of the out-going current as the last step in the treatment of said outgoing current prior to its being discharged into the atmosphere, and supplementing such treatment by injecting steam into the said incoming air current to supersaturate the same.

41. The process of bringing air to the proper condition of temperature and humidity for use in ventilation which comprises transferring from an outgoing air current to an incoming air current a portion of the heat carried by the outgoing air in excess of that carried by the incoming air, the said heat transfer being effected between the air of the incoming current during the first step in its treatment and the air of the outgoing current prior to its being discharged into the atmosphere, supplementing such treatment by injecting steam into the said incoming air current to further heat and to saturate the same, and heating the saturated air to the proper temperature to reduce its relative humidity to the desired standard.

42. The process of bringing air to the proper condition of temperature and humidity for use in ventilation which comprises transferring from an outgoing air current during the last step in its treatment prior to its discharge to the atmosphere, to an incoming air current during the first step in its treatment, a portion of the heat carried by the outgoing air in excess of that carried by the incoming air, supplementing such treatment by injecting steam into the said incoming air current to further heat and to supersaturate the same, separating from said incoming air current substantially all of the suspended water which it carries, and heating the saturated air to the desired temperature.

43. The process of conditioning air for the ventilation of buildings which comprises bringing an incoming air current into heat-transferring relationship with a body of water, bringing said body of water into heat transferring relationship with a second body of water, contacting said second body of water with an outgoing air current maintaining an evaporating chamber at a pressure at which water will boil at a tempera-

ture below that of the conditioned air, passing a body of water through said evaporating chamber to cool said water by partial evaporation thereof, conducting said cooled water into contact with the warmer of said air currents after the same has been in heat-transferring relationship with one of said first two bodies of water, returning said heated water to said evaporating chamber, continuously transferring vapor from said evaporating chamber into a condensing chamber, continuously circulating a fourth body of water through said condensing chamber to condense said vapor and to heat said water, contacting the so-heated water of said fourth body with the other of said air currents, and re-using said cooled water in said condensing chamber.

44. The process of conditioning air for ventilation of buildings which comprises scrubbing an incoming air current with a body of water, bringing said body of water into heat transferring relation to a second body of water, contacting the water of said second body of water with an outgoing air current, contacting the warmer of said air currents with a third body of water which is at a temperature below or approximating 60° F., the quantity of water of said third body contacted with said air being sufficient to cool said air to a temperature approximately 60° F., subjecting said third body of water to a partial vacuum sufficient to cause ebullition of the same to evaporate a portion of the water of said third body and to restore the same to approximately its initial temperature, transferring vapor evaporated from said third body of water to a condenser which is maintained at a pressure substantially above the pressure at which said vapor was generated, passing through said condenser a fourth body of water which is initially at a temperature below the boiling point of water at the pressure maintained in said condenser to condense said vapor and to heat said fourth body of water; and contacting the so-heated water of the said fourth body with the cooler of said air currents to re-cool the water of said fourth body and to heat said air.

45. The process of conditioning air for ventilation which comprises contacting the warmer of incoming and outgoing air currents with relatively cool water, bringing said air into intimate contact with a second body of water which is initially at a temperature below 65° F. to further cool said air and to heat said water, subjecting said heated water to evaporation under a partial vacuum until the water of said second body has been restored to its initial temperature, using the so-cooled water to cool a further portion of said warmer air, compressing the vapor evaporated from said water to a pressure corresponding to a saturation tempera-

ture above the initial temperature of the cooler air, condensing said vapor by bringing the same into heat-transferring relationship with a third body of water which is at 5 a temperature approximating the said initial temperature of the conditioned air, whereby the water of said third body is raised to a temperature above the said temperature of the cooler of said air currents, 10 and contacting the so-heated water with the said cooler air current.

46. The process of conditioning air for ventilation which comprises transferring, from the warmer to the cooler of incoming and outgoing air currents, as the first step in the treatment of the respective currents, a portion of the heat of said warmer air current in the direction of the natural temperature gradient between the two currents, and 20 transferring the remaining heat of the warmer air current to the cooler air current against the natural temperature gradient between the respective currents, as the second step in the treatment of the said currents, by evaporating water from a body of water maintained in heat-transferring relationship with said warmer air current and condensing the water vapor so formed in heat-transferring relationship with the said air current.

47. The process of conditioning air for ventilation which comprises transferring, from the warmer to the cooler of incoming and outgoing air currents as the first step in 25 the treatment of the respective currents, a portion of the heat of said warmer air current according to the natural temperature gradient between the two currents, and effecting the final conditioning of said incoming air current with regard to absolute 40 humidity by mechanically transferring heat from said warmer air current to said cooler air current against the natural temperature gradient between the two currents, as the 45 second step in the treatment of the respective currents.

48. The process of conditioning air for ventilation which comprises transferring a portion of the surplus heat from the warmer 50 to the cooler of incoming and outgoing air currents as the first step in the treatment of the two currents, cooling the said warmer air current to a temperature approximately corresponding to the dew point of the conditioned air as the second step in the treatment of the said warmer air, whereby water vapor is condensed from said air, and transferring to the cooler air current by mechanical agency, as the second step in its 55 treatment, a quantity of heat substantially equivalent to the heat sensible and latent abstracted from said warmer air current in said second step.

49. The process of conditioning air for

ventilation which comprises transferring 65 from the warmer to the cooler of incoming and outgoing air currents by indirect conduction a portion of the surplus heat of said warmer air current, as the first step in the treatment of the said currents, subjecting 70 the partially cooled air to further cooling to a temperature corresponding to the dew point of the conditioned air by evaporating water from a body of water maintained in heat-transferring relationship with said 75 warmer air current and condensing the water vapor so formed in contact with a body of water maintained in heat-transferring relationship with the said cooler air current, as the second step in the treatment of said 80 air current.

50. The process of conditioning air for ventilation which comprises transferring from the warmer to the cooler of incoming and outgoing air currents, as the first step 85 in the treatment of the respective currents, a portion of the heat of said warmer air current, further cooling said warmer air current down to a point substantially corresponding to the dew point of the conditioned 90 air by evaporating water from a body of water maintained in heat transferring relationship with said air current, and transferring to the said cooler air current as the second step in its treatment a quantity of heat 95 approximately equivalent to the total heat abstracted from said warmer air current in said second cooling step.

51. The process of conditioning air for ventilation which comprises transferring 100 from the warmer to the cooler of incoming and outgoing air currents, as the first step in the treatment of the respective currents, a portion of heat of the warmer air current, further cooling said warmer air current 105 down to a point substantially corresponding to the dew point of the conditioned air, converting heat abstracted from said warmer air in said second cooling step into latent heat of vaporization in a corresponding 110 quantity of water vapor, transferring said latent heat to the said cooler air current as the second step in its treatment by condensing the said water vapor in contact with a body of water maintained in heat-transferring 115 relationship with said cooler air current.

52. The process of conditioning air for ventilation which comprises transferring from the warmer to the cooler of incoming 120 and outgoing air currents, as the first step in the treatment of the respective currents, a portion of the heat of the warmer air current, further cooling said warmer air current down to a point substantially corresponding to the dew point of the conditioned air, converting heat abstracted from 125 said warmer air in said second cooling step

into latent heat of vaporization in a corresponding quantity of water vapor, transferring said latent heat to the said cooler air current as the second step in its treatment by 5 condensing the said water vapor in contact with a body of water maintained in heat-transferring relationship with said cooler air current, and finally conditioning said warmer air by subjecting the said air to partial reheating to the temperature desired.

53. The process of conditioning air for ventilation which comprises effecting a transfer of heat between the incoming and outgoing air by scrubbing the incoming air 15 with a body of water, scrubbing the outgoing air, as the first step in its treatment, with a second body of water, and establishing heat-transferring relationship in counter-current flow between the said first and second bodies of water, further cooling said warmer air by evaporating water from a body of water in heat-transferring relationship with said air, transferring the water vapor resulting from the evaporation of said 25 water to a condenser, condensing said water vapor by contacting the same with a circulating body of water maintained in heat-transferring relationship with the cooler air after the same has been heated as a result 30 of the said first step in its treatment, and finally conditioning said incoming air by heating the same to the temperature at which it is intended to be used.

54. The process of conditioning air for ventilation which comprises scrubbing incoming air with a body of water, scrubbing outgoing air, as the first step in its treatment, with a second body of water, and establishing heat-transferring relationship in 40 counter-current flow between the said first and second bodies of water, further cooling said warmer air down to a temperature substantially corresponding to the dew point of the conditioned air, by evaporating water 45 from a body of the same maintained in heat absorbing relationship with said partially cooled warmer air, contacting the cooler air with water after the said air has been partially reheated in said first treatment step, 50 withdrawing said water from contact with said cooler air, compressing the water vapor formed by the evaporation of water from the body of the same in contact with the said warmer air to a pressure corresponding to 55 that of saturated steam at a temperature above the temperature of the said water that has been contacted with the said used air in said second treatment step, contacting the said compressed vapor with said water to 60 condense said vapor and to heat said water, and returning said heated water to contact with said used air, whereby heat of said condensed vapor is transferred to said outgoing used air.

55. In a process of ventilation having incoming and outgoing air currents, the step of conditioning the incoming air which comprises evaporating a liquid with heat transferred from one of said air currents and condensing the vapors generated in a heat 70 contacting relation to the other air current.

56. In a process of ventilation having incoming and outgoing air currents, the step of conditioning the incoming air which comprises evaporating a liquid by heat transferred from one of said air currents, compressing the vapor generated and condensing the vapors in a heat contacting relation to the other air current.

57. In a process of ventilation having incoming and outgoing air currents, the step of conditioning the incoming air which comprises circulating a body of water into and out of contact with one of said air currents, withdrawing vapor from the water out of contact with said air current, circulating a second body of water into and out of contact with the other of said air currents, transferring to and condensing in said second body of water the vapor withdrawn from said first body of water.

58. The process of ventilation which comprises supplying air to rooms to be ventilated and withdrawing air from said rooms, and transferring heat from one of said air currents to the other of said air currents.

59. The process of ventilation which comprises supplying air to rooms to be ventilated, withdrawing air from said rooms, transferring heat from one of said air currents to the other of said air currents and maintaining equal pressures within and outside of said rooms.

60. In apparatus for ventilating, the combination of means for transferring heat from the outgoing to the incoming current or vice versa through the medium of a liquid, and means for bringing the incoming current to a standard degree of absolute humidity.

61. In apparatus for ventilating, the combination of means for transferring heat from the outgoing to the incoming current or vice versa by contacting first the warmer 115 of said currents and then the other of said currents with water maintained in circulation between the two currents, and means for bringing the incoming air current to the desired degree of absolute humidity.

62. In apparatus for ventilating, means for bringing the air for ventilation to the proper conditions of temperature and humidity, said means comprising in combination, means for transferring heat by conduction from the outgoing to the incoming air currents, means for supersaturating said incoming air with water vapor, and supple-

mentary heating means for raising the temperature of the said air current after the same has been saturated with water vapor.

63. In apparatus for bringing air used in ventilation to the proper condition of temperature and humidity, the combination of a water-washer in which the outgoing air current is contacted with a body of water, a water-washer in which the incoming air current is contacted with a second body of water and a heat interchanger in which excess heat of the warmer of the two bodies of water over the heat of the cooler of said bodies is transferred to the said cooler of the two bodies of water.

64. In apparatus for bringing air used in ventilation to the proper condition of temperature and humidity, the combination of a water-washer in which the outgoing air current is contacted with a body of water, a water-washer in which the incoming air is contacted with a second body of water, a counter-current heat interchanger in which the excess heat of one of said bodies of water is transferred to the other of said bodies of water, a spray chamber for loading the said incoming air current with a finely disseminated spray of water, a spray chamber for loading the said outgoing air current with a similar spray of water, and means for transferring heat from the water of one of said sprays to the water of the other of said sprays.

65. In apparatus for bringing air to the proper condition of temperature and humidity for ventilation, the combination of means for heating the incoming air current by the heat carried by the outgoing air current, means for introducing an excess of water vapor into the said incoming air current, means for removing substantially all suspended water particles from said incoming air current, and means for heating the saturated air to a temperature sufficient to compensate for the heat loss from said incoming air current during its passage through the building and to reduce its relative humidity to the point desired.

66. In apparatus for bringing air to the proper condition of temperature and humidity for ventilation, the combination of a water-washer for scrubbing the outgoing air current with a body of water which is initially at a lower temperature than the said air current, a water-washer for scrubbing the incoming air current with a second body of water, a counter-current heat interchanger for interchanging the temperatures of the respective bodies of water by transferring the excess heat of one body to the other body of water, means for introducing an excess of heated water into the said incoming air current to heat and supersaturate the same with water vapor, means for separating substantially all water particles

from said incoming air current, means for heating said saturated air to a temperature sufficient to bring the said air to the proper condition of temperature and humidity for ventilation.

67. In apparatus for bringing air to the proper condition of temperature and humidity for ventilation, the combination of a water-washer for scrubbing the outgoing air with a body of water, a water-washer for scrubbing the incoming air current with a second body of water, a heat interchanger for interchanging the temperatures of the respective bodies of water, means for contacting the incoming air current with water as a spray, means for removing the sprayed water from said air, and means for cooling the said water after the same has been heated by contact with the said air by subjecting the same to partial evaporation.

68. In apparatus for bringing air to the proper condition of temperature and humidity for ventilation, the combination of a water-washer for scrubbing the outgoing air with a body of water, a water-washer for scrubbing the incoming air current with a second body of water, a heat interchanger for interchanging the temperatures of the respective bodies of water, means for introducing water as a spray into the said incoming air current, means for separating the unevaporated portion of said water from said air, an evaporator for evaporating a portion of the said water after the same has been heated by contact with the said air, whereby the said water is restored to its original temperature, and means for transferring the latent heat of evaporation of the so-formed water vapor to the outgoing air current.

69. In an apparatus for bringing air to the proper condition of temperature and humidity for ventilation, the combination of a water-washer for scrubbing the outgoing air current with water, a water-washer for scrubbing the incoming air current with a second body of water, a counter-current heat interchanger for interchanging the temperatures of the respective bodies of water by transferring the excess heat of one body to the other body of water, a spray chamber for introducing water as a spray into the said incoming air current, means for separating the unevaporated portion of said water from said air, an evaporator for evaporating a portion of the said water after the same has been heated in contact with the said air, whereby the said water is restored to its original temperature, a condenser for condensing the water vapor generated in the said evaporator at a higher pressure than prevails in the said evaporator by a stream of water, a spray chamber for introducing the heated water from the said condenser into the outgoing air current as a

spray, and means for separating the unevaporated portion of the said sprayed water from said outgoing air current.

70. A heat transferring apparatus comprising in combination, an evaporator adapted to evaporate liquid to form vapor, said evaporator comprising means for forming a plurality of liquid curtains arranged in baffled formation and extending transversely 10 of said evaporator, means for conducting unevaporated liquid away from said evaporator, a vapor pump for exhausting from said evaporator the vapor formed therein, and a condenser for condensing the vapor 15 exhausted from said evaporator.

71. A heat-transferring apparatus comprising in combination an evaporator adapted to evaporate liquid to form vapor, a vapor pump for exhausting from said evaporator, 20 the vapor formed therein, and a condenser for receiving and condensing the vapor exhausted from said evaporator, said condenser comprising means for supplying liquid to said condenser, means for dividing 25 said liquid into a plurality of substantially parallel sheets in intimate contact with said vapor, said sheets extending transversely of said condenser and means for withdrawing uncondensed gases and liquid from said condenser.

72. A heat-transferring apparatus comprising in combination an evaporator adapted to evaporate liquid to form vapor, said evaporator comprising means for supplying liquid thereto, means for dividing said liquid into a plurality of sheets, and means 35 for withdrawing unevaporated liquid from said evaporator, a vapor pump for exhausting from said evaporator the vapor formed

therein, and a condenser for receiving and 40 condensing the vapor withdrawn from said evaporator, said condenser comprising means for supplying liquid thereto, means for dividing said liquid into a plurality of substantially parallel sheets in intimate contact 45 with said vapor, said sheets extending across said condenser and means for withdrawing uncondensed gases and liquid from said condenser.

73. A heat transferring apparatus comprising an evaporator adapted to evaporate liquid to form a vapor, a condenser adapted to condense said vapor and means for transferring said vapor from said evaporator to said condenser, the said evaporator and said condenser each comprising an inclosed chamber, a plurality of tiers of substantially horizontal troughs, the troughs of the adjacent tiers being arranged in staggered relation to each other and so spaced that the 50 troughs of the lower of any two adjacent tiers will intercept the fall of liquid discharged from the troughs of the upper of said adjacent tiers, a vertical slotted feed trough located transversely of the uppermost of said tiers of horizontal troughs, the vertical slots of said feed trough being arranged to register with corresponding troughs in the uppermost of said tiers of troughs, a barometric tube communicating 55 with the lower part of said inclosed chamber and adapted to drain liquid therefrom and a tank adapted to receive liquid from said barometric tube and to seal the lower orifice of said tube.

In testimony whereof I affix my signature.

HENRY L. DOHERTY.
